UNITED STATES PATENT OFFICE.

MARTIN M. HINER, OF HARRISBURG, PENNSYLVANIA.

CAR-BRAKE.

SPECIFICATION forming part of Letters Patent No. 298,467, dated May 13, 1884.

Application filed July 13, 1883. (No model.)

To all whom it may concern:

Be it known that I, MARTIN M. HINER, a citizen of the United States, residing in Harrisburg, Pennsylvania, have invented certain new and useful Improvements in Car-Brake Attachments; and I do hereby declare that the following is a full, clear, and exact description thereof, reference being had to the accompanying drawings, and to the letters of reference marked thereon, making a part of this specification.

In the forms of apparatus heretofore invented for this purpose none have been devised in which the brakes will work equally as well upon curves, and especially upon reversed curves, as upon straight portions of the track, or which will operate as well in long trains of forty or fifty freight-cars as in short trains.

20. The object of my invention is to obviate the defects incident to the existing forms of self-acting brakes in these respects, and by improving thereon to produce a complete automatic system which will actuate the ordinary 25 brakes, and which, without interfering with their application to any one car by hand in the customary manner, may, at the option of the engineer of the train, be brought into effective operation, so that whatever may be the 30 position of the train, whether on a reverse curve or on a straight track, the retardation of the engine or forward cars, when the train is in motion, shall operate to produce an automatic application of the brakes to each or 35 any car in the rear thereof, irrespective of the length of the train.

It consists in the combination, with two arms adapted, by means of suitable mechanism under the control of the engineer, to be projected 40 rearwardly from the locomotive or tender in line with the bumpers, of two longitudinally-traversing rods transversely connected, so as to move in unison, and so fitted under each car of the train as to extend, one on each side, 45 from bumper-head to bumper-head in line with the bumpers, so that the ends of the rods on each side of all the cars shall respectively come into contact when the bumpers are forced together, and shall also contact with the arms 50 on the locomotive or tender, when the latter are projected outwardly. These connected longitudinally-traversing rods serve to oper-

ate by their longitudinal movement the brake-levers of the car. When the two rods on the first car are forced inward by contact with the outwardly-projecting arms on the locomotive or tender at one end, they will both project outwardly at the other far enough to engage the corresponding rods on the next car brought, as aforesaid, directly in line therewith, so that the brake-levers on each car will thus be actuated in turn throughout the entire length of the train, when, by the movement of the engineer's lever, the locomotive brake-arms are thrown out, and an application of the brakes 65 to each and every car in the train will be thereby produced. If the train be upon a curve, the rods on the inner side will alone come into contact; but these will suffice to produce an application of the brakes. As the longitudinal rods admit of being straight from end to end, and each pair are rigidly connected and braced together, not only is sufficient strength attained with a comparatively light weight of rods, but the rods on the inner side of each 70 curve or bend of the train, when it is moving or standing upon a double or reverse curve, will be surely brought into operative contact.

In the accompanying drawings, Figure 1 is a bottom plan view of a car having my brake device applied thereto, the ordinary brake chains and appliances being omitted to avoid a confusion of lines; Fig. 2, a similar view, illustrating the brake-rods when moved to produce an application of the brakes; Fig. 3, a 85 side view of one of the actuating rods or tubes; and Fig. 4, a side view, illustrating the application of the brakes to the wheels of one of the trucks.

A is the bottom frame of the car, and B the trucks supporting the same upon the wheels C. The brake-shoes D, fitted upon cross-bars E E, swung by links F from the cross-head or bolster B of the truck, (see Fig. 4,) are brought to bear equally upon the front and rear wheels 90 in each truck by means of a lever, H, pivoted to one of the bars E, and having its shorter lower end connected by a rod, a, with the corresponding end of a second lever, H', pivoted in like manner as the lever H to the opposite bar E. (See Figs. 1 and 2.) The brakes are constructed and connected alike in both trucks, and the upper longer end of the actuating lever H of each is coupled with the corre-

sponding lever of the other by an equalizing-chain, G, which is led in its passage from one to the other around friction-rollers at the extremities of a transverse equalizing-bar, J, 5 pivoted centrally to a bearing-plate, K, under the center of the car. This bar is maintained automatically in its normal position at right angles to the length of the car by means of a spring, L.

10 M M are the two connected operative rods which extend the entire length of the car, each from a point in line with the face of a bumper, b, at one end of the car, to a point in line with the face of the corresponding bumper, b', at the 15 opposite end and below the same. The rods are bent outward centrally, so as to pass over the ends of the equalizing-bar J, as shown in Figs. 1 and 2, and each is led through a longitudinally-slotted plate, H², secured upon the 20 upper side of the bar. (See Fig. 3 and dotted lines, Fig. 2.) A sliding spring-actuated stop, i, is fitted upon each rod, to engage the slotted plate H² when the rod is moved longitudinally from its normal position in a given 25 direction. The stops upon the two rods are arranged each to engage the bar J from an opposite direction, so that one of the rods will always engage the equalizing-bar J in whichever direction they are pushed, and, forcing it 30 around, will thereby cause the brake-chain G to draw upon the brake-levers H H, and thus apply the brakes to the wheels. By this arrangement the equalizing-bar is actuated always in the same direction to apply the brakes, 35 irrespective of the direction in which rods M M may move. The rods are coupled to move together by means of cross-rods P P. (See Figs. 1 and 2.) Gas pipes or tubes may be employed to constitute these rods.

40 The ends of the connected rods M M are ordinarily inside of the ends of the bumpers, (see Fig. 1,) so that in the usual movements of the train when starting or running, either backward or forward, the rods remain inoperative, and the brakes, uninfluenced thereby, 45 may be operated by any of the usual appliances adapted to actuate either the equalizing-bar J or the brake-levers H or H. When, however, pressure is applied to the ends of the longitudinal brake-rods M M to push them inward in either direction, (see at lefthand in Fig. 2,) the result is an immediate application of the brakes to the car. This inward movement of the rods is effected upon the car 50 next to the locomotive by means of one or more arms, N N, (see Fig. 2,) adapted to be forced out from the rear end of the locomotive or tender into direct line with the end or ends of the longitudinal rod or rods under the 55 car by means of a lever to be actuated by hand or by steam, and which is under the control of the engineer. By pushing out one or both of these arms against the ends of the brake-rods, these brake-rods will be forced inward 60 at the front end of the car, and outward at the rear end, (see Fig. 2,) their longitudinal movement serving to apply the brakes in the

manner as described. As the car is thus arrested, the next car will be driven into close contact therewith by its momentum, and the 70 projecting ends of the brake-rods, brought thereby into contact with the ends of the brake-rods on this next car, will operate to move said rods, and thereby apply the brakes to that car, and thus the brake-rods of one 75 car, when brought into play, will operate to move the brake-rods of the next throughout the entire length of the train. So soon as the engineer draws back the brake-arms on the locomotive and starts the engine forward, the 80 entire series of brakes will be released. So long as the brake-arms are not projected to engage the rods, the train may be operated as if my automatic brake arrangement were not 85 connected therewith.

It will be observed that a direct contact is produced between the ends of the operating arm or arms on the rear of the tender with the ends of the longitudinal rods under the next car, and between the ends of the said 90 rods under the several cars, so that when brought together the rod or rods form, substantially, a continuous rod from end to end of the train without the interposition of any mechanical devices whatever.

The connected longitudinally-traversing brake-rods M M may be applied to any of the lever-brakes now in use upon freight-cars.

The devices for applying the longitudinal movement of the rods to the operation of the 100 brakes are such as will readily suggest themselves to the practical mechanic, and need not therefore be herein enumerated or described.

I do not herein claim a single rod running longitudinally and centrally under the bottom 105 of the car, with its ends projecting under the draw-heads at the middle of each end of the car, to be operated by the outward thrust of a central rod adapted to be projected from the tender or locomotive, and by its longitudinal 110 movement operate the brakes on the car, as shown in the Letters Patent to A. Codd, No. 260,942, of July 11, 1882, for upon a trial of substantially the same device prior to the date of said patent I found it inoperative when 115 the cars are running upon a curve, and useless on freight-trains of ordinary length on account of the lost motion involved; nor do I claim two separate rods moving independently 120 of each other, as described in the patent to J. W. Glover, No. 156,284, of October 27, 1874, as the brakes could not thereby be applied automatically to all the cars of a train moving over a reverse curve, as in my invention.

I claim as new, and desire to secure by Let- 125 ters Patent—

In a system for automatically applying the brakes upon the cars of a railway-train through the momentum of the train, the combination, with each car and with its brake appliances, 130 of a frame constructed of two continuous rods connected by cross-bars, and mounted to have jointly free longitudinal play under the car, each longitudinal rod of the frame being made

to extend the entire length of the car, on either side thereof, from bumper-head to bumper-head, in position to align and contact directly with a counterpart projecting arm or rod on the locomotive or tender, and to produce by its rearward movement in unison with its parallel rod an application of the brakes on the car, substantially in the manner and for the purpose herein set forth.

In testimony whereof I have signed my name to this specification in the presence of two subscribing witnesses.

MART. M. HINER.
